Patented Dec. 16, 1975

238,076

WALL MOUNTED HOUSING FOR AN AIR CONDITIONER OR SIMILAR ARTICLE

Jon M. Newgard and Charles F. Schultz, Louisville, Ky.,
assignors to General Electric Company

Filed Oct. 15, 1974, Ser. No. 514,375

Term of patent 14 years

Int. Cl. D23—04

U.S. Cl. D23—141

FIG. 1 is a perspective view of a wall mounted housing for an air conditioner or similar article showing my new design, the side not shown is a mirror image of that shown and the bottom is flat and unornamented;

FIG. 2 is a sectional view taken on line 2—2 of FIG. 1 through the front inlet grill.

We claim:

The ornamental design for a wall mounted housing for an air conditioner or similar article, as shown and described.
